TREATMENT OF HYDROCARBON OILS

Jean Delattre Seguy, Chicago, Ill., assignor to
 Universal Oil Products Company, Chicago,
 Ill., a corporation of South Dakota

Application March 24, 1932, Serial No. 600,842

4 Claims. (Cl. 196—49)

This invention relates more particularly to the conversion of liquefiable components separated from so called uncondensable gases resulting from cracking of hydrocarbon oil for the purpose 5 of producing fixed gas and more stable liquid products.

In the type of cracking operation where distillate and gas from the fractionator of the system are collected at substantially atmospheric 10 or low superatmospheric pressure, the so called uncondensable gas will contain appreciable amounts of liquefiable components which may be recovered by further cooling or refrigeration and/or compression. These condensable hydro- 15 carbons may comprise principally propane, methane, and their corresponding unsaturates as well as butane, pentane and in many cases appreciable quantities of hexane. Also, a portion of some of the heavier hydrocarbons normally contained within the distillate will not be condensed 20 by the methods ordinarily employed and will remain entrained in the gases.

The present invention is particularly concerned with the treatment of this type of material, which 25 may be separated from the gaseous products resulting from the conversion of hydrocarbon oils.

It is well known that cracking or pyrolytic conversion produces materials both lighter and heavier than the charging stock and it is also well 30 recognized that relatively high temperature vapor-phase cracking is ordinarily accompanied by polymerization reactions. I have found that by subjecting the liquefiable components of gases resulting from cracking to suitable conditions of 35 reconversion and commingling the resulting products with the total products of the same cracking reaction in which the materials subjected to treatment were formed, the final products will show increased recovery of desirable light liquid 40 products and a somewhat increased volume of fixed gas. It is my belief that a portion of the increased liquid recovery may be accounted for by polymerization during retreatment of the condensables recovered from the gas and, in part, 45 by the action of the products of such retreatment upon the higher boiling products of the cracking reaction.

The attached diagrammatic drawing illustrates one specific form of apparatus wherein the process 50 of the present invention may be practiced. Raw oil charging stock for the system may be supplied through line 1 and valve 2 to pump 3 from which it may be fed through line 4 and valve 5 into fractionator 6, serving the purpose of partially 55 cooling and assisting fractionation of the

vapors in this zone and being thereby preheated. The preheated raw oil, charging stock, together with reflux condensate comprising the relatively heavy components of the vapors condensed by fractionation is withdrawn from the lower portion of the fractionator through line 7 and valve 8 to pump 9 from which it is fed through line 10 and valve 11 to heating element 12 for conversion. When desired, a portion or all of the raw oil instead of passing overhead to fractionator 6 may be directed from pump 3 through line 13 and valve 14 directly into line 10 and thence to heating element 12, together with reflux condensate from the fractionator.

Heating element 12 is located within a furnace 15 of any suitable form and the oil supplied thereto is heated to the desired conversion temperature, preferably at substantial superatmospheric pressure and is thence discharged through line 16 and valve 17 into reaction chamber 18.

Reaction chamber 18 is also preferably maintained at substantial superatmospheric pressure and in the particular case illustrated, this chamber is of the type wherein the vaporous conversion products are subjected to continued conversion time while liquid products, which separate from the vapors and gravitate more rapidly to the bottom of the chamber, are subjected to conversion in this zone for a much shorter time than 30 the vapors. The total products, both liquid and vaporous, are withdrawn simultaneously from chamber 18 through line 19 and valve 20 and are introduced at reduced pressure into vaporizing chamber 21.

Reduced pressure chamber 21, in the case here illustrated, comprises the lower portion of fractionator 6, being separated from the fractionator by a suitable tray or deck 22 through which the vapors from chamber 21 may pass to the fractionator and upon which reflux condensate from the fractionator may collect. It will be understood that the chamber 21 may, when desired, be a separate piece of equipment connected to the fractionator by a vapor-line, although this arrangement is not illustrated in the drawing. Residual liquid remaining unvaporized in chamber 21 may be removed therefrom through line 23 controlled by valve 24 to cooling and storage or to any desired further treatment or, when desired, conditions may be so controlled in the vaporizing chamber that only substantially dry coke remains as the residual product of the system; in which case this product may accumulate within the chamber 21 to be removed therefrom 55

after the operation of the chamber is completed and, when desired, a plurality of chambers (not shown) may be employed for the accumulation of coke and may be operated either alternately or simultaneously.

Vapors from the chamber 21 pass through the vapor outlet 25 into the fractionator 6 wherein their relatively heavy components are condensed as reflux condensate, to be removed therefrom and subjected to further treatment, as already described. Fractionated vaporous products pass from the upper portion of fractionator 6 through line 26 and valve 21, are subjected to condensation and cooling in condenser 28, from which the 10 condensed and uncondensed products pass through line 29 and valve 30 to be collected in receiver 31. The condensed distillate may be withdrawn from receiver 31 through line 32 and valve 33. A portion of this product may, when 15 desired, be recirculated, by well known means not shown, to the upper portion of fractionator 6 for the purpose of regulating the vapor outlet temperature from this zone and to assist fractionation.

Products remaining uncondensed in receiver 31 are withdrawn therefrom through line 34 and valve 35 to compressor 36, by means of which the pressure thereon is substantially increased for the purpose of liquefying their high boiling components. When desired, a refrigerating or cooling coil 38 may be utilized in conjunction with or instead of compressor 36. When utilized in conjunction with the compressor, products from the compressor pass through line 37 and thence 20 through line 39 and valve 40 into the coil 38, immersing therefrom through line 41 and valve 42 back into line 37 and thence through valve 43 into the separator 44. When the cooling coil is not used, it may be by-passed by means of valve 45, in line 37. Means for by-passing compressor 36 are well known and not here illustrated. Final separation of liquid and gaseous products is effected in separator 44. The gases may be released therefrom through line 46 and valve 47. 25 The separator is preferably maintained under the increased pressure generated by compressor 36 in order to prevent vaporization of the liquefied products and in case the refrigerating or cooling coil is used, separator 44 and the connecting lines 30 may be heavily insulated.

The liquefied components of the uncondensed products from receiver 31 which accumulate in separator 44, are withdrawn therefrom through line 48 and valve 49 to pump 50 by means of 35 which they may be supplied through line 51 and valve 52 to a separate heating element 53 wherein they are subjected, by means of heat supplied from furnace 54, of any suitable form, to a conversion temperature of the order of about 1200 40 to 1600° F., at a pressure which may range from about 100 to 1000 pounds, or more, per square inch.

A separate reaction zone 55 may be provided to permit continued conversion of the heated materials, in which case the heated materials from heating element 53 pass through line 56, line 57, valve 58, reaction chamber 55 and are withdrawn therefrom through line 59, passing through valves 60 and 61 into line 19 and thence to vaporizing 65 chamber 21. When it is not desired to use reaction chamber 55, it may be by-passed by closing valves 58 and 60 and opening valve 62, in line 66, thus passing materials from heating element 53 through line 56, valve 62, line 58, valve 61 and 70 line 19 direct to vaporizing chamber 21. It is

obvious that, when desired, instead of commingling the products from reaction chamber 55 and the products from heating element 53 or reaction chamber 55, in line 19, they may enter vaporizing chamber 21 through separate lines.

When the nature of the liquefiable components recovered from the cracked gases is such that they may be advantageously retreated under relatively mild conversion conditions of the order of 950 to 1050° F., and substantial superatmospheric pressure, and when the nature of the charging stock for the cracking operation is such that these same conditions give good results for its conversion, heating element 53 and reaction chamber 55 may be dispensed with and the liquefied products from separator 44 may be supplied from pump 50 through line 51, line 63 and valve 64 into line 10, commingling therein with the other oils to be cracked and passing therewith to heating element 12, for further conversion.

The heating element to which the raw oil charging stock and reflux condensate from the fractionator are supplied may utilize conversion temperatures ranging, for example, from 875 to 1050° F. with superatmospheric pressures of the order of 100 to 800 pounds, or more, per square inch in this heating element and the succeeding reaction chamber, the vaporizing, fractionating, condensing and collecting portions of the system 25 preferably utilize relatively low pressure of the order of 100 pounds or thereabouts down to substantially atmospheric pressure. Substantial superatmospheric pressure up to several hundred pounds per square inch is, however, preferably 30 employed in the separator to which the compressed and/or cooled gases from the receiver are directed. As previously mentioned, temperatures in the heating element to which the liquefied components of the gases are supplied, may range 35 from 1200 to 1600° F., or thereabouts with a pressure in this zone and in the succeeding reaction chamber, when the latter is used, ranging preferably from 100 to 1000 pounds, or more, per square inch.

To more clearly illustrate the features and advantages of the process, let us first consider a cracking operation not utilizing the present invention. The raw oil charging stock is a Mid-Continent topped crude of about 31° A. P. I. gravity which is subjected, together with reflux condensate from the fractionator of the system, to a temperature in the heating element of about 920° F. The heating element and reaction chamber are maintained at a superatmospheric 40 pressure of approximately 350 pounds per square inch. The vaporizing chamber and succeeding portions of the system are maintained at a substantially equalized pressure of approximately 50 pounds per square inch. This operation may result in the production of about 64%, based on the raw oil, of 400° F. end point motor fuel having an octane number of approximately 68, about 27% of residual oil, the remaining 9% based on the charging stock being chargeable to gas, loss 45 and a small percentage of coke.

When the above operation is modified by the incorporation of the features of the present invention, gas from the receiver of the system is compressed under a pressure of about 500 pounds 50 per square inch and then cooled to about 40° F. The resulting liquids are subjected in a separate heating element to a temperature of about 1200° F. under a pressure of approximately 500 pounds per square inch and are introduced into the va- 55

porizing chamber of the cracking system. By this method the yield of motor fuel may be increased to approximately 72% of the charging stock and may have an anti-knock value equivalent to an octane number of approximately 75. The residual oil is reduced to coke, which may amount to approximately 50 pounds per barrel of charging stock and the yield of gas is substantially increased.

10 In another type of operation carried out in accordance with the present invention, the raw oil charging stock is a Pennsylvania straight-run gasoline containing a naphtha fraction boiling up to approximately 500° F. which is subjected, in 15 the heating element, to a temperature of about 950° F. under a superatmospheric pressure of approximately 800 pounds per square inch. Substantially this same pressure is maintained in the reaction chamber, which is reduced in the vaporizing chamber to approximately 50 pounds per square inch, and substantially equalized in the succeeding fractionator, condenser and receiver. The heavy components of the gas are subjected 20 to liquefaction under about the same conditions as mentioned above and the recovered liquid is returned to the same heating element to which the charging stock and reflux condensate are supplied. This operation may yield, based on the 25 charging stock, about 90% of motor fuel having an octane number of approximately 80, the remaining products being gas and a small amount of coke.

I claim as my invention:

1. In a process for the conversion of hydrocarbon oil wherein the oil is subjected to conversion conditions of elevated temperature and superatmospheric pressure in a heating coil and reaction chamber and thereafter discharged into a reduced pressure chamber where vapors separate from non-vaporous residue, the vapors being subjected to fractionation followed by condensation and collection of resulting distillate and uncondensed products, the improvement which comprises subjecting the latter, following their separation from the distillate, to liquefaction to effect the removal of their high boiling components, subjecting the recovered liquid to further conversion at a higher temperature than that employed in the first mentioned heating coil and introducing said heated liquid into the reduced pressure chamber.

2. A process for the conversion of hydrocarbon oils to produce maximum yields of motor fuel of good anti-knock characteristics which comprises subjecting the oil to conversion conditions of elevated temperature, and superatmospheric

pressure in a heating element, introducing the heated material into a reaction chamber, withdrawing the total products from the reaction chamber and subjecting them to vaporization at reduced pressure in a vaporizing chamber, subjecting the vapors to fractionation, subjecting the fractionated vapors to condensation, collecting the resulting distillate and uncondensed products, liquefying and separating from the latter their high boiling components, subjecting the recovered liquid to further conversion at a temperature higher than that employed in the first mentioned heating element, and introducing them into the vaporizing chamber.

3. A process for the conversion of hydrocarbon oils to produce maximum yields of motor fuel of good anti-knock characteristics which comprises subjecting the oil to conversion conditions of elevated temperature and superatmospheric pressure in a heating element, introducing the heated material into a reaction chamber, withdrawing the total products from the reaction chamber and subjecting them to vaporization at reduced pressure in a vaporizing chamber, subjecting the vapors to fractionation, returning the heavy components of the vapors condensed by fractionation to the heating element for further conversion, subjecting the fractionated vapors to condensation, collecting the resulting distillate and uncondensed products, liquefying and separating from the latter their high boiling components, removing the unliquefied gases from the system, subjecting the recovered liquid to further conversion at a temperature higher than that employed in the first mentioned heating element, passing the highly heated materials through a separate reaction zone and thence introducing them into the vaporizing chamber.

4. A conversion process which comprises subjecting hydrocarbon oil in a cracking zone to cracking temperature under sufficient pressure to maintain a substantial portion thereof in liquid phase, discharging the cracked oil into a separating zone maintained under lower pressure than the cracking zone and separating the same therein into vapors and residue, fractionating and then finally condensing the vapors and separating resultant condensate from uncondensed gases, separating higher boiling components from the uncondensed gases and subjecting the same in an independent conversion zone to higher conversion temperature than the oil in the first-named zone, and then introducing the thus treated higher boiling components into said separating zone.

JEAN DELATTRE SEGUY.
